UNITED STATES PATENT OFFICE

GEORGE R. PEAR, OF LYNN, MASSACHUSETTS, ASSIGNOR TO THE STEAM HEATED HORN COMPANY, OF PORTLAND, MAINE, AND BOSTON, MASSACHUSETTS.

SHOE-SEWING MACHINE.

SPECIFICATION forming part of Letters Patent No. 533,665, dated February 5, 1895.

Application filed February 5, 1894. Serial No. 499,070. (No model.)

To all whom it may concern:

Be it known that I, GEORGE R. PEAR, of Lynn, in the county of Essex and State of Massachusetts, have invented certain new and useful Improvements in Steam-Joints for Shoe-Sewing Machines, of which the following is a specification.

This invention relates to an improved construction of steam-joint for use between the rotary horn of a shoe-sewing machine of the McKay type and its support, whereby steam may be conducted to the horn and wax-pot after the manner disclosed in Patent No. 405,592, granted to me June 19, 1889.

One object of the present invention is to provide a construction whereby the weight of the horn may be utilized to maintain the joint steam-tight.

Another object is to effectually prevent access of the drip of condensation to the gear on the whirl-driving spindle.

A further object is to provide for lubricating the bearings by means of the condensation.

To the above ends, the invention consists in the novel construction and arrangement of parts hereinafter described and claimed.

The invention is illustrated in the accompanying drawings.

Figure 1 shows a vertical section of the joint and parts of a shoe-sewing machine with which it is connected. Fig. 2 shows a cross-section of the female member of the joint. Fig. 3 shows a bottom plan view of the male member. Fig. 4 shows a side elevation of the male member. Fig. 5 shows a plan of the female member.

The letter *a* designates the supporting arch of the frame of the machine; *b*, the hollow shank of the horn; and *c*, the spindle which transmits motion to the whirl, said spindle extending vertically through the arch and carrying a bevel-pinion, *c'*, below the same, to receive motion from the driving means.

The parts above enumerated are common to shoe-sewing machines of the McKay type, to which my invention is applicable.

A sleeve, *d*, is fitted tightly in the arch, *a*, and extends vertically therethrough and projects above the same. Said sleeve surrounds the spindle, *c*, and has a bushing, *c''*, at the

lower end, forming a bearing for said spindle. An extension, *d'*, of the sleeve, thinner than the sleeve itself, extends upward therefrom and forms a shield to prevent condensation which collects in the hollow shank from passing down along the spindle to the gear on the lower end of the same, and being thrown about by said gear.

The letter *e* designates the female member or socket of the steam-joint, which seats on the arch, *a*, and is held from turning by pins, *e'*. Said member, *e*, has a central opening to accommodate the sleeve, *d*, and is recessed in the under side around said opening, as at *e''*, to receive packing, *e''*, and a ring, *e'''*, forming a steam-tight joint around the sleeve. The member *e* has a central boss which is recessed in the upper side at the middle, so as to form a series of annular seats, *e⁴*, *e⁵*, *e⁶*, around the sleeve rising one above the other, as steps, and is further recessed outside the central boss, to form a cup, *e⁷*, in which condensation may accumulate and from which it may escape through a pipe, *e⁸*. Ports, *f* and *f'*, extend out of the vertical walls, *f²* and *f³*, which rise from the annular seats, *e⁵* and *e⁶*, respectively, and a steam-supply pipe, *g*, enters the member, *e*, and communicates with the port, *f*, and an exhaust-pipe, *g'* enters the opposite side of the member, *e*, and communicates with the port, *f'*. A shell, *h*, is mounted on the member, *e*, and forms an upward extension of the cup, *e⁷*.

The male member, *i*, of the steam-joint is formed with a series of annular stepped shoulders, *i'*, *i²*, *i³*, which rest on the seats, *e⁵*, *e⁶*, *e⁷*, respectively, of the female member. In the portions of the male member extending between the shoulders, *i'* and *i²*, and *i²* and *i³*, annular passages, *i⁴*, and *i⁵*, are made and communicate respectively with the ports, *f* and *f'*. Passages, *i⁶* and *i⁷*, extending through the member, *i*, connect the passages, *i⁴* and *i⁵*, respectively with pipes *j* and *j'*, fastened in arms of the member, *i*, and one, *j*, adapted to conduct steam to the horn and the other, *j'*, adapted to return the steam and condensation.

The horn-shank, *b*, seats in a recess in the upper side of the member, *i*, and is prevented from turning therein by a pin, *k*. The horn is fitted with a bushing, *k'*, which closely sur-

rounds the sleeve, *d*. It will now be seen that the weight of the horn is received on the seats, *e*⁵, *e*⁶, and *e*⁷, and leakage between them and the shoulders, *i*¹, *i*², and *i*³ thereby prevented. 5 The fit of the male member, *i*, around the sleeve, *d*, permits it to rotate freely on the same. These bearings are lubricated through the following provisions: the passage, *i*⁷, is extended in half its cross-sectional area (see Fig. 3) down to the seat, *e*⁵, and said passage emerges from the shoulder, *i*², in its full cross-sectional area, and thus extends partly over the seat, *e*⁶. The passage, *i*⁷, is extended in half its cross-sectional area down to the seat, *e*⁶, and extends over that part of the latter not covered by the passage, *i*⁶. Said passage, *i*⁷, emerges in its full cross-sectional area from the shoulder, *i*³, and thus extends partially over the seat, *e*⁷. The remainder of said seat 10 is covered by a notch, *m*, in the shoulder, *i*³. That part of the lowest seat, *e*⁷, not covered by the passage, *i*⁶, is provided for by a groove, *m*', extending along the bore of the member, *i*, and through the bushing, *k*', and allowing 15 lubricant to pass down from the interior of the horn to the lower seat. It will now be seen that provision is made for lubricating the bearings throughout all their lateral extent. 20 25 30 Condensation, which might work itself between the joint-members and the sleeve, *d*, would be prevented from passing down along the sleeve by the packing, *e*⁸, and would be obliged to rise along the sleeve and enter the hollow horn, from which it would be discharged through a passage, *n*, into the cup, *e*⁸. In the operation of the machine, steam entering through the pipe, *g*, passes into the annular passage, *i*⁴, and traverses the same until it finds the passage, *i*⁶, through which it is conducted to the pipe, *j*, and therethrough to the horn. The steam and condensation return from the horn through the pipe, *j*', the passage, *i*⁷, the annular passage, *i*⁵, the port, 45 *f*', and pipe, *g*'. It is to be understood that the invention is not limited to the structure here shown, but is capable of embodiment in other forms. Having thus described my invention, what 50 I claim as new, and desire to secure by Letters Patent, is—

1. In a shoe-sewing machine, the combination with a rotary horn, of a stepped bearing therefor of steam joint comprising a female member having a series of annular stepped seats and steam inlet and outlet ports in the walls extending from the seats respectively, and a male member having stepped annular shoulders fitting the seats of the female member, annular passages in the walls extending

from said shoulders, said passages communicating with the inlet and outlet ports respectively, and steam supply and exhaust passages communicating with said annular passages respectively. 65

2. In a shoe-sewing machine, the combination with a rotary horn, of a stepped bearing therefor of steam joint comprising a female member having a series of annular stepped seats and steam inlet and outlet ports in the walls extending from the seats respectively, and a male member having stepped annular shoulders fitting the seats of the female member, annular passages in the walls extending from said shoulders, said passages communicating with the inlet and outlet ports respectively, and steam supply and exhaust passages communicating with said annular passages respectively,—communications being provided between said passages and the annular seats and shoulders for purposes of lubrication, substantially as described. 70 75 80

3. The combination, with the rotary hollow horn-shank and the whirl-driving spindle extending therethrough, of a fixed sleeve surrounding said spindle and extending up into the horn-shank, and a steam-joint comprising two members surrounding said sleeve, one being stationary and the other arranged to rotate with the horn-shank. 85 90

4. The combination of a fixed support, a sleeve affixed therein and projecting upward therefrom, a whirl-driving spindle extending through said sleeve, a socket or female member of a steam-joint surrounding the sleeve 95 and affixed to the support, said socket having stepped seats and steam inlet and outlet ports above the seats, respectively, packing interposed between said socket and the sleeve, a male member of the steam-joint stepped to fit 100 the female member and having annular passages communicating with the ports thereof, and steam supply and exhaust passages communicating with the annular passages and connecting with pipes which extend to the 105 horn, a hollow horn-shank surrounding the upward projecting portion of the sleeve and affixed to the male member of the steam-joint, and a cup supported by the female member of the joint and surrounding the lower portion of the horn-shank. 110

In testimony whereof I have signed my name to this specification, in the presence of two subscribing witnesses, this 26th day of January, A. D. 1894.
